Lacey, Lacey,

ATTORNEY'S

UNITED STATES PATENT OFFICE.

SANTO LO MONACO, OF CLEVELAND, OHIO.

RAILROAD RAIL.

Application filed August 1, 1928. Serial No. 296,750.

This invention relates to railroad rails and one object of the invention is to provide a rail adapted to be engaged by the flange wheels of railroad cars and so formed that the wheels 5 will be retained upon the rails and prevented from moving off them if the trucks of a car attempted to shift transversely of a track. It often happens that when a car is moving 10 along a track having rails of a conventional construction the trucks will shift transversely if the rails are worn or not properly spaced from each other thereby allowing the car to tilt and turn over on one side but by having the rails constructed in accordance with this 15 invention such tilting will be prevented.

Another object of the invention is to provide a rail formed with a center groove in its head and having passages leading from the groove or channel so that water accumulating 20 in the groove from rain or melting snow may pass out of the groove instead of freezing therein and forming ice which would be liable to cause the wheels of a car to leave the track.

Another object of the invention is to form 25 the rail with drain openings leading from the groove or channel through the web and base of the rail and so located that they will not cause the rail to be weakened.

The invention is illustrated in the accompanying drawing, wherein

Figure 1 is a top plan view of a section of a track and showing the improved rails in place;

Fig. 2 is an enlarged transverse sectional view through the track taken on the line 2—2 of Fig. 1, and

Fig. 3 is a perspective view showing a fragment of one of the improved rails with a portion thereof disclosed in transverse section.

In Figure 1, there has been shown a portion 40 of a track which may be of any length desired and includes ties 1 spaced from each other the usual distance and serving to support rails 2 which are secured upon the ties by the usual 45 spikes 3. The rails may be of any length and weight desired and each is formed with a wide base 4 supporting an upstanding web 5 at the upper end of which is formed a head 6. The head projects from opposite sides of the 50 web an equal distance, as clearly shown in Fig. 2, and the upper or tread surface of the head is formed with a longitudinally extending groove or channel 7 which is of greater depth than the flange of a car wheel, such as indi- cated by dotted lines in Fig. 2 and designated 55 by the numeral 8. By having the grooves of greater depth than the flanges of the wheels, there will be no danger of the flanges resting upon the bottoms of the grooves and thereby causing the flanges to be broken or 60 the wheels to leave the rails. During rainy weather or when snow is melting, water would collect in the grooves formed in the rails and would be liable to freeze, and in order to prevent water from accumulating in the 65 grooves, I provide each rail with a number of drain passages 9 which extend vertically through the web of the rail, as shown in Figs. 2 and 3, with their upper ends communicat- 70 ing with the groove and their lower ends opening through the under surface of the base of the rail. Therefore, the water may easily drain out of the groove. Some of these drain openings might become obstructed or water may gather in a groove faster than 75 it could drain out of the same through the passages 9, and I have, therefore, provided the head of the rail with recesses 10 which correspond in depth to the groove and extend transversely of the rail head at one side of 80 the groove. By having the recesses of the same depth as the groove they will be flush with the bottom thereof and water can easily flow from the groove through these recesses. It will thus be seen that water can very easily 85 pass out of the groove through the passages 9 and recesses 10 and will not be liable to freeze in the groove. Since the recesses are at the opposite side of the groove from the portion of the head upon which the wheel 90 rests, they will not prevent car wheels from rolling smoothly along the rail. It should also be noted that since the groove is located directly above the web and midway its thick- 95 ness the passages 9 will not cause the rail to be unduly weakened thereby eliminating danger of a broken rail. When a car is moving along a track, the wheels rest upon the rails and the flanges of the wheels are received in the grooves. If a car attempts to shift trans- 100 versely in either direction, this movement will be stopped by the flanges of the wheels con- tacting with side walls of the groove formed in the rails and, therefore, the wheels cannot leave the rails and also the car will be pre- 105 vented from tilting transversely and turning over. I have, therefore, provided a rail which will be strong and durable and so constructed

that ice will be prevented from forming in its groove and a car prevented from being liable to turn over.

Having thus described the invention, I claim:

A track rail having a base, an upstanding web, and a head carried by said web and having a channel formed longitudinally in its tread surface, the rail being formed with ¹⁰ drain passages leading from the bottom of

the channel in spaced relation to each other longitudinally thereof, one wall of the channels having transversely extending recesses formed therein and having open upper ends, and constituting drains leading from one side 15 of the channel and opening through a side face of the head to discharge water upon one side of the head.

In testimony whereof I affix my signature.
SANTO LO MONACO. [L. S.]
